UNITED STATES PATENT OFFICE.

EDWARD H. McCLOUD, OF COLUMBUS, OHIO, ASSIGNOR, BY MESNE ASSIGNMENTS, TO
THE KINNEAR MANUFACTURING COMPANY, OF COLUMBUS, OHIO, A CORPORATION
OF OHIO.

FIRE-RESISTING SHUTTER.

1,376,820.

Specification of Letters Patent.

Patented May 3, 1921.

Application filed April 2, 1919. Serial No. 286,900.

To all whom it may concern:

Be it known that I, EDWARD H. McCLOUD, a citizen of the United States, residing at Columbus, in the county of Franklin and 5 State of Ohio, have invented a certain new and useful Improvement in Fire-Resisting Shutters, of which the following is a specification.

The present invention relates to the type 10 of means for releasing automatic shutters or doors shown and described in the Letters Patent of the United States, No. 1,257,273 issued to me February 19, 1918.

In the use of the structure of that patent 15 if it be desired to release the shutter for the purpose of ascertaining whether it is in proper working condition it is necessary to move or disturb the slide or movable member carrying the fusible link.

20 It is one of the objects of the present invention to provide a construction of the type referred to in which the other advantages of that type are retained and the shutter made releasable without disturbing the member that carries the thermally actuated member.

The invention is embodied in the example herein shown and described, the features of novelty being finally claimed.

30 In the accompanying drawings—

Figure 1 is an elevation of the upper right hand corner as viewed from the interior of a building showing a window equipped with an automatic shutter and my 35 present invention as applied thereto.

Fig. 2 is a vertical section mainly on the line II—II Fig. 1 looking to the right.

Fig. 3 is a horizontal section on the line III—III Fig. 2 looking down.

40 In the views 5 designates one end of a shaft (spring holding or otherwise) of the winding drum upon which the shutter is wound, said shaft containing a star wheel 6 adapted to be engaged by a tooth 7 on a lever 8 to prevent the star wheel from turning in one direction.

In the present instance the fulcrum pin 8^a of the lever 8 is extended and furnished with a pulley 9 having a grooved rim while 50 the lever itself carries a small pulley 9^a journaled in a suitable bracket on the lever and having a grooved rim in line with the grooved rim of the pulley 9.

55 12 designates a slide or movable member carrying a hook 14. The slide lies in a me-

tallic box or frame 16 permanently installed in the wall of the building, said slide being open at its upper side within the wall, but having a hooded end 16^a with an opening below where it protrudes beyond the building. The slide 12 is held in the exposed end of the box by means of a pair of rods 13 threaded at their outer ends into the slide, said rods being held in position by means of a clip 15 and a bolt and nut clamping the 65 inner ends of the rod to the foot or a cast iron member 17 at the inner end of the box.

10 designates a chain, wire or other flexible member containing a fusible link 11 which is engaged with the hook 14 and then 70 passed inward under the pulley 9^a and thence upward over the pulley 9, through an elbow 18, a guiding eye 19 and downward to any suitable device for fastening the same. (Not shown.) The flexible member 10 is 75 thus doubly flexed by the pulleys 9 and 9^a.

To hold the star wheel 6 from turning the lever 8 is raised until its tooth is engaged with the desired tooth of the star wheel and the flexible member 10 drawn taut and fastened. The lever 8 can be drawn up into 80 position to cause its tooth 7 to engage the star wheel by drawing upon the flexible member, and reversely said lever can be released from that position by manually slackening the flexible member. This last operation 85 is performed when it is desired to test the shutter.

In case of near-by fire the heat acts on the fusible member 11 and releases the flexible 90 member and permits the operation of the shutter in the same way.

With the present construction as distinguished from the construction of my former patent hereinbefore referred to it is not necessary to move the slide or its hook 11 to test the shutter. The shutter can be tested as before indicated by simply slackening the flexible member and the lever 8 replaced to its holding position by drawing down on the 100 flexible member.

The forms of the parts can be changed without departing from the gist of the invention as claimed.

What I claim is:

1. In combination with an automatically closing fire shutter or door, means for latching the shutter, flexible means for actuating the latching means, thermally operated means in said flexible means, a slide with 110

which said actuating means is connected for exposing said thermally operated means and means on the latching means operated by the flexible means without displacing the slide 5 to cause the latching means to be brought into and out of latching position.

2. In combination with an automatically closing fire shutter or door, means for latching the shutter, flexible means for actuating the latching means, thermally operated means in said flexible means, a slide with which said actuating means is connected for exposing said thermally operated means and means on the latching means including a 10 pulley operated by the flexible means without displacing the slide to cause the latching means to be brought into and out of latching position.

3. In combination with an automatically closing fire shutter or door, means for latching the shutter, flexible means for actuating

ing the latching means, thermally operated means in said flexible means, a slide with which said actuating means is connected and means on the latching means including two 25 pulleys traversed by the flexible means and operated by the flexible means to cause the latching means to be brought into and out of latching position.

4. In combination with an automatically closing fire shutter or door, means for latching the shutter, a flexible member for actuating the latching means, thermally operated means in said flexible member, a slide with which said actuating member is connected for exposing the thermally operated means, and means in connection with the latching means for doubly flexing said flexible member whereby the latching means may be swung into or out of latching position without displacing the slide. 30 35 40

EDWARD H. McCLOUD.
